CLAIM

The ornamental design for a dashboard with a steering wheel, as shown and described.

DESCRIPTION

FIG. 1 is a front view of a dashboard with a steering wheel showing the new design;

FIG. 2 is a left-side view thereof;

FIG. 3 is a right-side view thereof;

FIG. 4 is a top view thereof; and,

FIG. 5 is a perspective view thereof.

The broken lines in the figures show unclaimed environmental structure and unclaimed portions of the article, and form no part of the claimed design.

1 Claim, 5 Drawing Sheets(56)
